(57) **CLAIM**

The ornamental design for a remote control, as shown and described.

DESCRIPTION

FIG. 1 is a front view illustrating our design for a remote control;

FIG. 2 is a left side view thereof;

FIG. 3 is a right side view thereof;

FIG. 4 is a rear view thereof;

FIG. 5 is a bottom view thereof; and,

FIG. 6 is a top view thereof.

The letters, numbers, and symbols (including the smiley face and paw toes) in broken lines in the figures form no part of the claimed design. Furthermore, the broken lines illustrated in FIG. 4 also form no part of the claimed invention.

The outermost broken-line oval in FIG. 4 represents the boundary between claimed and unclaimed areas. Neither the broken lines nor the areas within them form any part of the claim.
